DRINK DISPENSER OR THE LIKE

Richard J. Skiera, Chicago, Ill., assignor to Karma Corp.,
Addison, Ill., a corporation of Illinois

Filed Aug. 28, 1964, Ser. No. 81,499

Term of patent 14 years

(Cl. D2—3)

FIG. 2 is a perspective view taken from the side opposite to that shown in FIG. 1; and

FIG. 3 is a side view thereof.

I claim:

The ornamental design for a drink dispenser or the like, as shown.
